HIS ATTORNEY.

UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

DRILL-STEEL COUPLING

Application filed July 12, 1930. Serial No. 467,394.

This invention relates to couplings, but more particularly to a coupling adapted to secure together sections of drill steel, such as may be employed with rock drills.

5 Drill steels of great length, such as are frequently used in deep hole drilling operations, are cumbersome to transport and when broken at any point must be replaced in their entirety. To avoid these difficulties I 10 contemplate using a drill steel of built-up construction comprising two or more sections joined by my improved coupling.

The primary object of the present invention is to enable drill steel sections to be 15 connected in such manner that they will not become separated by jarring or rotation of the drill steel.

Another object of the invention is to enable drill steel sections to be quickly connected and disconnected.

A further object of the invention is to reduce the amount of breakage of couplings of this type.

Other objects will be in part obvious and in 25 part pointed out hereinafter.

In the drawings illustrating the invention and in which similar reference characters refer to similar parts,

Figure 1 is a sectional elevation of a drill 30 steel coupling constructed in accordance with the practice of the invention and operatively connecting a pair of drill steel sections,

Figure 2 is a transverse view taken on the line 2-2 of Figure 1 looking in the direction indicated by the arrows, and

Figure 3 is a transverse view taken on the line 3-3 of Figure 1 looking in the direction indicated by the arrows.

Referring to the drawings, A and B designate 40 drill steel sections which it is desired to secure together. The section A is an extension member and may comprise a body portion C and identical shank portions D at either end of the body portion C. Between the body portion C and the shanks D are formed one or more lateral lugs E herein shown as a pair of diametrically opposed lugs similar to those used on standard drill steels of the Leyner type. The upper portion of the section A (not shown) is adapted to be engaged by

the chuck parts of a rock drill in a well known manner whereby rotation of the chuck parts will be transmitted to the drill steel. The section A is adapted to be secured at its lower end to the section B by means which shall be 55 more fully described hereinafter.

The section B may be of standard drill steel of the Leyner type and accordingly is shown carrying a cutting bit F at its lower end. Near the upper end of the section B may 60 be formed a pair of chuck engaging lugs G similar to the lugs E and dividing the section B into a body portion H and a shank J. The sections A and B preferably are of equal diameter and if desired may be provided with 65 longitudinally extending registering passages K for conveying cleansing fluid to the drill hole.

In accordance with the present invention the shanks D and J are adapted to be inserted into the bore L of a coupling sleeve O from the opposite ends thereof. Preferably the diameter of the bore L is only slightly greater than the diameters of the shanks D and J so that misalignment of the sections 70 A and B will be avoided. The combined lengths of the shanks D and J should exceed the length of the bore L so that the shanks may bear against each other when assembled thus assuring the direct transmission of force 75 from the section A to the section B.

The means employed for preventing relative endwise movement of the sections A and B and to enable the transmission of rotary movement of the section A to the section B 80 comprises in this instance a pair of retaining nuts P and Q which preferably are identical in all essential respects. The nuts P and Q are provided with axial threaded sockets R to receive correspondingly threaded end portions S and T respectively of the sleeve O. The nuts P and Q are also provided with reduced bores U in one end coaxial with the sockets S to permit the insertion of the shanks D and J into the bore L. Preferably 85 the sleeve O is provided with an enlarged intermediate portion V the diameter of which may be substantially equal to the external diameters of the nuts P and Q, and the diameters of each of these members should 90

be somewhat smaller than the diameter of the cutting bit F.

In each of the nuts P and Q between the recesses S and the bores U are formed chuck

5 cavities W which are somewhat similar in cross section to a shape which would be generated by the lugs E and G upon oscillation of the section A or B about their longitudinal axes. In order to enable the lugs E and G

10 to enter the chuck cavities W of the nuts P and Q respectively, slots X may be formed in the nuts P and Q in the longitudinal plane of the bores U. The slots X are so located with respect to the cavities W that rotation

15 of the sections A and B may cause the lugs E and G to bear against the walls Y of the cavities W in which position they will be out of alignment with the slots X thus locking said sections within the nuts P and Q.

20 I contemplate employing the force of rotation of the drill steel to assure a tight connection between the coupling and the drill steel sections A and B. To this end I arrange the slots X so that the normal tendency 25 toward relative rotation of the sections A and B, caused by rotative movement imparted to the section A and resistance to rotation afforded by the bit F, will hold the lugs E and G against the walls Y. I also select the

30 direction of threads on the sleeve O and the nuts P and Q with reference to direction of rotation of the drill steel so that the tendency toward relative rotation of the nuts P and Q will cause the nuts to become more tightly 35 threaded on the threaded ends S and T of the sleeve O. This involves threading the nut P onto the end S in the direction of rotation of the drill steel and threading the nut Q onto the end T in the direction opposed to

40 the direction of rotation of the drill steel.

Due to the fact that the nuts P and Q will be drawn up tightly on the opposite ends of the sleeve O the shanks D and J will be caused to bear firmly against each other, thereby 45 sealing the cleansing fluid passages K at the juncture of the sections A and B. To facilitate the disconnection of the drill steel sections, the nuts P and Q may be provided with suitable wrench receiving surfaces Z.

50 In assembling the device, the nuts P and Q may first be threaded on the reduced ends S and T respectively by means of a suitable tool to a point at which the ends S and T will be spaced slightly from the bottom of the

55 sockets R. The sections A and B may then be inserted into the aligned bores U and L to a point at which the lugs E and G will occupy a position within the chuck cavities W of the nuts P and Q respectively. By rotating the sections A and B the lugs may be carried into locking positions in the chuck

60 cavities W and upon screwing the nuts tightly on the ends S and T the adjacent ends of the shanks D and J will be carried into abutting relation. The drill steel will then be

ready for connection to a drilling machine.

In order to assure easy disconnection of the sections A and B it is desirable that lugs E and G do not contact with the ends of the sleeve O. By applying wrenches to the surfaces Z of each nut P and Q and exerting a force to rotate the nuts in opposite directions one or both of the nuts may be unscrewed to a slight extent from the sleeve O. This permits either of the sections A and B 70 to be rotated to carry the lugs thereon into alignment with the slots X whereupon the sections may be removed from the coupling by endwise movement.

75 In this construction the threads never become either cut or jammed by blows imparted to the drill steel by the rock drill, and although the connection is secure it is always possible to detach the parts without difficulty.

80 I claim:

85 1. In a coupling, the combination of a pair of members disposed in end to end contacting relation, a coupling sleeve adapted to receive the adjacent ends of the members, a lug on each of the members, and nuts threaded on the ends of the coupling members and bearing against the lugs to press the adjacent ends of the members firmly together.

90 2. In a coupling, the combination of a pair of members disposed in end to end contacting relation, a coupling sleeve adapted to receive the adjacent ends of the members, a lug on each of the members, and nuts threaded in opposite directions on the opposite ends of the coupling sleeve and bearing against the lugs to press the ends of the members together.

95 100 3. In a coupling, the combination of a pair of members disposed in end to end contacting relation and having smooth adjacent end portions, a coupling sleeve adapted to slidably receive the adjacent end portions of the members, a lug on each of the members, and nuts threaded on the ends of the coupling sleeve and engaging said lugs to draw the members into abutting relation within said coupling sleeve.

105 4. In a coupling, a female member having a bore and a wall at one end of the bore, a male member adapted to be slidably received in the bore, a lug on the male member, a nut having a threaded recess to receive said female member and an opening to receive the male member, a slot in one end of the nut to allow insertion of the lug therein when the nut is assembled on the female member, a cavity in the nut at one end of the slot to permit the male member to be rotated within the nut for carrying the lug out of alignment with the slot, and a wall in the cavity to bear against the lug for transmitting rotation of the nut to the male member.

110 120 125 5. In a coupling, the combination of a pair of members disposed in end to end relation, a coupling sleeve adapted to slidably receive

the adjacent ends of the members, nuts threaded on the opposite ends of the coupling sleeve and having openings in their outer ends to receive the members, slots in the 5 outer ends of the nuts to allow insertion of the lugs into the nuts, cavities communicating with the slots to permit rotation of the members in the nuts to carry the lugs out of alignment with the openings, said nuts seating adjacent the legs to press the adjacent ends of the members firmly together.

10 In testimony whereof I have signed this specification.

CHARLES C. HANSEN.
